UNITED STATES PATENT OFFICE

131,476

DESIGN FOR A FISH LURE

Levin B. Cook, Shreveport, La., assignor of one-half to Haskell R. Miller, Shreveport, La.

Application June 4, 1941, Serial No. 101,302

Term of patent 3½ years

To all whom it may concern:

Be it known that I, Levin B. Cook, a citizen of the United States, residing at Shreveport, in the county of Caddo and State of Louisiana, have invented a new, original, and ornamental Design for a Fish Lure, of which the following is a specification, reference being had to the accompanying drawing, forming part thereof.

I claim:

The ornamental design for a fish lure, as shown.

LEVIN B. COOK.
